UNITED STATES PATENT OFFICE.

WILLIAM A. SMITH, OF EASTON, PENNSYLVANIA, ASSIGNOR TO INGERSOLL-RAND COMPANY, OF JERSEY CITY, NEW JERSEY, A CORPORATION OF NEW JERSEY.

MOUNTING FOR DRILLS.

1,358,889.

Specification of Letters Patent. Patented Nov. 16, 1920.

Application filed June 28, 1918. Serial No. 242,413.

To all whom it may concern:

Be it known that I, WILLIAM A. SMITH, a citizen of the United States, residing at Easton, in the county of Northampton and 5 State of Pennsylvania, have invented a certain new and useful Improvement in Mountings for Drills, of which the following is a specification.

This invention relates to percussive tools 10 and in particular to a mounting for a fluid operated percussive drill to hold and guide the drill within the shell while it is in operation.

The objects of the present invention are 15 to provide a mounting or carriage for percussive drills which will be simple, durable, and readily assembled and which will form a rigid support for the drill cylinder.

A further object of the invention is to 20 provide a mounting or carriage having guides on either side adapted to fit the guideways of a shell and to provide the mounting or carriage with a feed nut at its rear end to engage the feed screw usually 25 provided as a part of the shell.

With these and other objects in view my 30 invention consists in the features of construction and operation set forth in the following description and illustrated in the accompanying drawings, forming a part 35 hereof, in which

Figure 1 shows a percussive tool cylinder with the mounting of the present invention partially connected thereto, some of the 40 parts being in section; and

Fig. 2, a longitudinal view of the drill cylinder mounting and shell partially in section.

Referring more particularly to the drawings, 45 1 refers to the drill cylinder of a fluid operated percussive drill such as a hammer drill provided with means to be more fully described hereafter for attaching it to the mounting. The drill cylinder 1 may be of any desired type, the one shown having a motor casing 2 at its front end and a reduced cylinder bore 3 in its forward part joining the enlarged bore 4 extending to its rearward part.

At the forward end of the cylinder 1 is provided the usual chuck 5 for holding the drill steel 6, and at the rear end the back head 7 sets against the cylinder, the chuck 5 and back head 7 being held together by 55 the side bolts 8 firmly holding all of the above parts together.

Extending downwardly from the motor casing 2 which forms a part of the cylinder body is a lug 9 having a hole 10 passing horizontally and transversely therethrough and at the rear of the cylinder 1 is a transverse horizontal notch 11. It is by these means that the cylinder is held in position on the carriage or mounting. The carriage 12 at its forward end is provided with two lugs 13 each having a hole bored horizontally therethrough similar to and of the same size as the hole 10, the lugs being separated sufficiently to permit the lug 9 on the motor casing 2 to pass between them, thus bringing the holes through the lugs on the mounting into alignment with the hole 10 in the lug on the motor casing. A pin 15 extends through each of the holes provided in the lugs 9 and 13, thus rotatively holding the mounting or carriage 12 and drill cylinder body 1 together.

At the rear of the mounting or carriage 12 depends a lug 14 having a longitudinal hole extending therethrough in which is located the feed nut 16 through which passes the feed screw 17 rotatively mounted in the shell 18 and by means of which the drill is advanced and withdrawn from the rock during its operation.

Surrounding the feed nut 16 is a clamping member 19 having a projection 20 at its upper edge, adapted to fit into the notch 11 provided in the cylinder 1. On its lower edge another projection 21 is provided parallel to the projection 20 and which is adapted to take up on an inclined portion 22 of the lug 14 when the nut 23 is tightened. It will be seen from the above description that when the nut 23 is tightened it not only securely holds the feed nut 16 in place but also holds the cylinder body 1 against the mounting or carriage 12 by means of the engagement of the clamping member 19 with the notch 11 in the cylinder.

This connection between the notch 11 and clamping member 19 supplements the connection of the cylinder body 1 and motor casing 2 to the lugs 13 on the mounting at the forward end to provide a rigid and permanent mounting of the drill cylinder 1 and the mounting.

It is to be understood that the present showing and description disclose only one specific embodiment of the present invention and that other forms and modifications are included within the spirit and scope of the

invention, as expressed in the appended claims.

What I claim is:

1. In a mounting for percussive tools, in combination a shell, a feed screw, a cylinder body provided with a lug at its forward end and a portion at its rear end having a notch therein, a carriage mounted on said shell and adapted to pivotally engage said cylinder body at its forward end and a clamp secured to said carriage and engaging said notch to hold said cylinder body and carriage together.
2. In a mounting for percussive tools, in combination a shell, a feed screw, a cylinder body, provided with a lug at its forward end and a portion at its rear end having a notch therein, a carriage mounted on said shell and having a pin engaging the lug on the cylinder body and a clamping member engaging the notch on said carriage whereby said cylinder body and carriage are held rigidly together.
3. In a mounting for percussive tools, a shell, a feed screw and feed nut, a carriage mounted on said shell and arranged to be fed therealong by means of said feed screw and nut, a tool cylinder attached to said carriage at one end and clamping means at the other end of said carriage arranged to engage said cylinder body, carriage and feed nut to secure said cylinder body, carriage and feed nut in position.
4. In a mounting for percussive tools, a shell, a feed screw and feed nut, a carriage mounted on said shell and arranged to be fed therealong by said feed screw and nut, a tool cylinder pivoted to said carriage at one end and clamping means at the other end of said carriage arranged to engage said cylinder body, carriage and feed nut and secure said cylinder body, carriage and feed nut in position.
5. In a mounting for percussive tools, a shell, a feed screw and feed nut, a carriage mounted on said shell and arranged to be fed therealong by said feed screw and nut, a tool cylinder pivoted to said carriage at its forward end and clamping means at the rearward end of said carriage arranged to engage said cylinder body, carriage and feed nut and secure said cylinder body, carriage and feed nut in position.
6. In a mounting for percussive tools, a shell, a feed screw and feed nut, a carriage mounted in said shell and arranged to be fed therealong by means of said feed screw and nut, a tool cylinder body pivoted to the forward end of said carriage, and clamping means surrounding the feed screw at the rearward end of said carriage for engaging said cylinder body, carriage and feed nut to secure said cylinder body, carriage and feed nut in position.
7. In a mounting for percussive tools, a shell, a feed screw and feed nut, a carriage mounted on said shell and arranged to be fed therealong by means of said feed screw and nut, a tool cylinder body pivoted to the forward end of said carriage and clamping means secured to the rearward end of said carriage and moving with the carriage as it is fed along the shell for engaging said cylinder body, carriage and feed nut to secure said cylinder body, carriage and feed nut in position.
8. In a mounting for percussive tools, a shell, a feed screw and feed nut, a carriage mounted on said shell and arranged to be fed therealong by means of said feed screw, a tool cylinder body provided with a lug at its forward end and arranged to be pivoted to the forward end of said carriage by means of lugs on said carriage, the said cylinder body having a notch at its rearward end and clamps secured to said carriage in a manner to engage said notch and hold said cylinder body, carriage and feed nut in position.
9. In a mounting for percussive tools, a shell, a feed screw and feed nut, a carriage mounted on said shell and arranged to be fed therealong by means of said feed screw and nut, a tool cylinder body attached to said carriage at one end and a common means serving to secure the cylinder body to the carriage at the other end and to secure the feed nut in position relative to the carriage.
10. In a mounting for percussive tools, a shell, a feed screw and feed nut, a carriage mounted on said shell and arranged to be fed therealong by means of said feed screw and nut, a tool cylinder body attached to said carriage at one end and a common means on said feed screw serving to secure the cylinder body to the carriage at the other end and to secure the feed nut in position relative to the carriage.
11. In a mounting for percussive tools, a shell, a feed screw and feed nut, a carriage mounted on said shell and arranged to be fed therealong by means of said feed screw and nut, a tool cylinder body attached to said carriage at one end, and a single clamping means for simultaneously securing the cylinder body, carriage and feed nut, in position.
12. In a mounting for percussive tools, a shell, a feed screw and feed nut, a carriage mounted on said shell and arranged to be fed therealong by means of said feed screw and nut, a tool cylinder body attached to said carriage at one end, and a single clamping means on said feed screw for simultaneously securing the cylinder body, carriage and feed nut in position.
13. In a mounting for percussive tools, a shell, a feed screw and feed nut, a carriage mounted on said shell and arranged to be fed therealong by means of said feed screw and nut, a tool cylinder body attached to said carriage at one end, and a single clamping means on said feed screw for simultaneously securing the cylinder body, carriage and feed nut in position.

fed therealong by means of said feed screw and nut, a tool cylinder body attached to said carriage at one end and clamping means at the other end comprising a bolt and nut for exerting pressure longitudinally of the cylinder body, against a clamping member, for securing said cylinder body, carriage and feed nut in position.

14. In a mounting for percussive tools, a shell, a feed screw and feed nut, a carriage mounted on said shell and arranged to be fed therealong by means of said feed screw and nut, a tool cylinder body attached to said carriage at one end and clamping means on said feed screw comprising a bolt and nut at the other end for exerting pressure longitudinally of the cylinder body, against a clamping member for securing said cylinder body, carriage and feed nut in position.

15. In a mounting for percussive tools, a shell, a feed screw and feed nut, a carriage mounted on said shell and arranged to be

fed therealong by means of said feed screw and nut, a tool cylinder body attached to 25 said carriage at the forward end and clamping means at the rear end comprising a bolt and nut for exerting pressure longitudinally of the cylinder body, against a clamping member for securing said cylinder body, 30 carriage and feed nut in position.

16. In a mounting for percussive tools, a shell, a feed screw and feed nut, a carriage mounted on said shell and arranged to be fed therealong by means of said feed screw 35 and nut, a tool cylinder body attached to said carriage at the forward end and clamping means on said feed screw at the rear end comprising a bolt and nut for exerting pressure longitudinally of the cylinder 40 body, against a clamping member for securing said cylinder body, carriage and feed nut in position.

In testimony whereof, I have hereunto set my hand.

WILLIAM A. SMITH.
